ATTORNEY

UNITED STATES PATENT OFFICE.

MAX LEVY, OF NEW YORK, N. Y.

YARN-HOLDER.

1,386,264.

Specification of Letters Patent.

Patented Aug. 2, 1921.

Application filed March 4, 1920. Serial No. 363,262.

To all whom it may concern:

Be it known that I, MAX LEVY, a citizen of the United States, residing at New York city, in the county of New York and State 5 of New York, have invented certain new and useful Improvements in Yarn-Holders, of which the following is a specification.

My invention relates to a thread or yarn holder for knitting and crocheting.

10 In knitting or crocheting the operator usually winds a part of the yarn over one finger, partly for the purpose of keeping the yarn under suitable tension and partly to facilitate its feed to the work. As the yarn 15 is wound about and pulled over the finger it produces considerable friction, not infrequently causing discomfort and at times injury to the operator.

The principal object of my invention is to 20 provide a yarn holder or guide by means of which the yarn may be kept out of contact with the finger and still held under suitable tension to facilitate the knitting or crocheting operation.

25 I have illustrated the preferred form of my invention in the accompanying drawing, in which Figure 1 is a perspective view of a human hand with the device applied to the small finger thereof, and Fig. 2 is an elevational view of the yarn holder removed from the finger.

The yarn holder 10 is of spiral or helical form so as to readily encircle a finger, and is preferably made of spring metal to allow 30 of adjustment for fingers of various sizes. The helix is formed of what may be termed open tubing, being of a form to inclose the 35 yarn 11 but slit at 12 either at intervals or throughout its length. The purpose of the

slit 12 is twofold viz.:—to allow of access 40 to the yarn within the holder, if for any reason this is desired, and also to permit the walls adjacent the slit 12 to be more or less depressed to regulate the tension of the yarn dependent either on the nature of 45 the work, on the character of the yarn used, or both.

While in Fig. 2 the holder is shown as applied to the small finger of the operator, it will be understood that this is entirely 50 optional, and that the holder may be used on any finger to which the operator desires to apply it. Owing to the springy or resilient character of the device it may be placed on fingers varying considerably in 55 thickness, and for the same reason the device, when once applied, may be more or less tightly pressed about the finger.

I claim:—

1. A yarn holder, comprising a helix of 60 open tubing, each coil of the helix being adapted to yieldingly directly engage a human finger whereby said yarn holder is capable of being held without locking means on fingers differing in thickness. 65

2. A yarn holder, comprising a spring metal helix slotted lengthwise and having walls adjacent the slotted portion capable of adjustment in relation to the yarn in the holder, each coil of the helix being adapted 70 to yieldingly directly engage a human finger whereby said yarn holder is capable of being held without locking means on fingers differing in thickness. 75

In testimony whereof I have affixed my signature.

MAX LEVY.
